(57) **CLAIM**

The ornamental design for a chair, as shown and described in the drawing figures.

DESCRIPTION

FIG. 1 is a front elevation view of my new chair;
FIG. 2 is a back elevation view thereof;
FIG. 3 is a side elevation view thereof; and,
FIG. 4 is a top plan view thereof.

The drawing figures of front, side, top and rear views are shown. The chair includes a plain and unornamental flat bottom which is not shown.
